Des. 241,725
Patented Oct. 5, 1976

241,725

LINEAR CLOCK

James R. Bailey, 4020 N. Pioneer Ave.,
Chicago, Ill. 60614

Filed Apr. 25, 1975, Ser. No. 571,647

Term of patent 14 years

Int. Cl. D10—01

U.S. Cl. D10—15

FIG. 1

FIG. 2

FIG. 1 is a front perspective view of a linear clock showing my new design;

FIG. 2 is a front perspective view of another embodiment of my new design of FIG. 1.

The top and right sides of FIGS. 1 and 2 are identical with those shown, the rears being flat, plain and unornamented.

I claim:

The ornamental design for a linear clock, as shown and described.
